UNITED STATES PATENT OFFICE.

JOHN L. WAGNER, OF TERRE HAUTE, INDIANA, ASSIGNOR OF TWO-THIRDS
TO THOMPKINS A. LEWIS, OF INDIANAPOLIS, INDIANA, AND HENRY R.
DUVALL, OF NEW YORK, N. Y.

CAR-DOOR FASTENER.

SPECIFICATION forming part of Letters Patent No. 298,124, dated February 5, 1884.

Application filed July 12, 1883. (No model.)

To all whom it may concern:

Be it known that I, JOHN L. WAGNER, of the city of Terre Haute, county of Vigo, and State of Indiana, have invented certain new and useful Improvements in Car-Door Fasteners, of which the following is a specification.

The object of my said invention is to provide a fastener for swinging doors, which shall also serve to force said doors tightly shut, and to start said doors when it is desired to open them. This object is accomplished by attaching a crank-rod to the front edge of the door, and providing catches on the wall of the car or other structure, with which the cranks on the ends of said rod will engage, as will be hereinafter more particularly described.

My invention is especially designed for use in connection with refrigerator-cars, such cars being usually provided with thick swinging doors, which, in order that the cars may be kept of the proper temperature, it is necessary should be shut very tight.

Referring to the accompanying drawings, which are made a part hereof, and on which similar letters of reference indicate similar parts, Figure 1 is a side elevation of a car having doors provided with my said invention; Fig. 2, a horizontal sectional view, looking downwardly from the dotted line *z z* on an enlarged scale, the doors being closed; Fig. 3, a similar view, the doors being partly open; Fig. 4, a vertical sectional view, looking to the right from the dotted line *y y*; Fig. 5, a detail view of a portion of Fig. 4 on a still further enlarged scale; Fig. 6, a view similar to Fig. 5, except that the crank is shown as turned around and disengaged from the catch; and Fig. 7, a perspective view of substantially the parts shown by Fig. 5.

In said drawings, the portions marked A represent the car-body; B B', the doors; and C, the crank-rod, which is the main feature of my improved fastener. The car A is constructed, generally, in the ordinary manner, or in any manner suitable to adapt it to its purposes. It is provided with the catches *a a*, with which the ends of the rod C engage. The doors B B' are preferably the heavy hinged doors ordinarily used with refrigerator-cars,

and one of said doors has bearings for the rod C. It will be understood, of course, that double doors are shown simply as illustrative of the usual manner of applying my invention, and that it can be equally as well applied to a single door, if desired, the front edge of the door B' simply serving as a jamb for the door B so far as my invention is concerned in the construction shown. The rod C is mounted in bearings on the door B, and has cranks *c* upon its ends, which are adapted to engage with the catches *a* on the car-body and secure the doors in closed position. Said rod is also provided with a handle, C', by which it is thrown around from one position to another. When the door is in closed position this handle is adapted to engage with the staple *c'* on the door B', (or on the side of the car, if no second door is employed,) and be there secured by a pin, *b'*, or a lock. The handle is so arranged in relation to the cranks that when said handle is swung around against the door B' said cranks pass somewhat beyond a position at right angles with the face of the car, as shown most plainly in Fig. 2, and thus, being held from any outward movement by the catches *a*, exert a cam force upon the doors, which drives them tightly shut. These cranks can also be arranged, as shown, to come in contact with that portion of the car-body immediately behind them, or iron plates thereon, and thus as said rod is started around in the reverse direction, in order that the door may be opened, will start said door slightly from its close contact with its jambs and with the other door, and render the labor of opening said door much less than if hand-force alone had to be relied on.

In operation, after the doors are swung shut, the operator throws the handle C' around from the position shown by Fig. 3 to that shown by Fig. 2, which carries the cranks around the points of the catches *a*, and, finally, into the position shown by Fig. 2, forcing the doors closely shut, and, when said doors and the other portions of the car are properly constructed, rendering the car practically air-tight. In opening the operation is simply reversed, as above specified.

Having thus fully described my said inven-

tion, what I claim as new, and desire to secure by Letters Patent, is—

1. The combination, with a door and its jambs, of a crank-rod mounted on said door, 5 and catches secured to said jambs, with which the cranks of said rod are adapted to engage, substantially as described, and for the purposes specified.

2. The combination of the car A, having 10 catches *a a*, the hinged door B, and the rod C, having cranks *c c*, substantially as set forth.

3. The combination of the car, catches thereon, the doors mounted on hinges, the crank-rod, the cranks thereon, and the handle therefor, substantially as shown and specified.

In witness whereof I have hereunto set my hand and seal, at Indianapolis, Indiana, this 9th day of July, A. D. 1883.

JOHN L. WAGNER. [L. S.]

In presence of—

E. W. BRADFORD,
CHAS. L. THURBER.
